UNITED STATES PATENT OFFICE.

JAMES B. SMITH AND YANCY D. LOTT, OF JACKSON, MISSISSIPPI.

ELECTRIC-LIGHT CUT-OFF.

No. 892,095.

Specification of Letters Patent.

Patented June 30, 1908.

Application filed December 18, 1906, Serial No. 348,480. Renewed March 4, 1908. Serial No. 419,198.

To all whom it may concern:

Be it known that we, JAMES B. SMITH and YANCY D. LOTT, citizens of the United States, residing at Jackson, in the county of 5 Hinds, State of Mississippi, have invented certain new and useful Improvements in Electric-Light Cut-Offs; and we do hereby declare the following to be a full, clear, and exact description of the invention, such as 10 will enable others skilled in the art to which it appertains to make and use the same.

This invention relates to automatic electric light cut-offs, and more particularly to that class which are time-controlled and the 15 primary object of the invention is to provide a cut-off of this class which may be applied to any alarm clock now on the market and to any snap switch without in any way altering the construction of the same.

20 The device is particularly useful in stores and the like where it is desirable to leave the lights in the show windows lighted for a considerable time after the store has been closed, the device being designed to cut off the lights 25 at a predetermined time.

Broadly speaking, the device embodying our invention comprises, in combination with the alarm spring winding shaft of a clock, a winding drum upon the said shaft, 30 an arm secured to the handle of the switch to be operated, and connection between the winding drum and the arm whereby unwinding of the spring upon the winding shaft will rotate the drum and wind the connection 35 thereon in this manner exerting a pull upon the arm which is connected with the switch handle. Heretofore such connections have been in the nature of cords but we have conceived the idea of interposing in such a connection a spring which constitutes a potential 40 device and which stores the power generated from the alarm spring until sufficient power has been generated to swing the arm and actuate the switch.

45 In the accompanying drawings: Figure 1 is a view in elevation of our device in use, Fig. 2 is a top plan view thereof, Fig. 3 is a detail view of the switch arm showing its construction before being attached to the key of the 50 snap switch.

Referring more specifically to the drawings, there is shown an alarm clock 5 having the usual flat piece 6 for winding the alarm spring and there is also shown a common 55 form of snap switch 7 including the usual key

8, it being understood, of course, that the snap switch controls the supply of current to the lamps (not shown).

A disk 9 is grooved peripherally as at 10 and is provided with a slot 11 in which is received a flat key 6 upon the clock 5. A pin 12 is seated in this groove and to the pin is connected one end of a cord 13. The other end of this cord is connected to a coil spring 14 and to the spring is also connected one 15 end of a cord 15, this last-named cord being provided at its free end with a heavy elastic ring 16.

In order that the clock 5 may be firmly supported so that it will not be overturned 70 when the snap switch is operated, in a manner to be hereinafter described, a strip of metal 17 is secured at one of its ends as at 18 to a shelf 19 and is engaged over the clock and detachably connected at its other end as 75 at 20 to a coil spring 21 which in turn is secured to the shelf 19, it being understood that the resiliency of the spring 21 is exerted to cause the strip 17 to snugly embrace the upper portion of the clock.

In order to secure sufficient leverage to permit actuation of the snap switch an arm 22 is provided and one end of the arm is flattened as at 23 sufficiently to permit of its being bent and the flattened portion is provided with tongues 24 which are bent to engage the inner edge of the key 8 of the snap switch, the flattened portion 23 being, of course, bent to inclose the greater portion of the key. After the arm has been connected 90 with the key of the snap switch, the rubber ring 16 is engaged in a groove 25 formed in the upper end of the arm 22, this engagement being had, of course, after the alarm spring has been wound up. The alarm is 95 then set and when sprung will wind the cord upon the disk 9 and move the arm 22 to turn the switch key. The spring 14 serves to cause quick closing of the switch as the spring will be stretched to some degree before sufficient force has been exerted to close the switch.

From the foregoing description of our invention and as heretofore stated, the spring 14 is in effect a potential device and stores 105 up the energy generated by the alarm spring, as the said spring unwinds, until the required amount of power has been generated to actuate the arm which is connected to the switch handle.

What is claimed is:—

1. The combination with a clock having an alarm spring winding shaft and a switch, of an arm secured to the handle of the switch, 5 a winding drum upon the alarm spring winding shaft, flexible connection between the drum and the arm, and an elastic power storing element interposed in said connection.
- 10 2. The combination with the button of a snap switch and with the winding key of an alarm clock, of an arm having an integral plate portion provided with prongs, the plate portion and the prongs being adapted 15 to be bent to embrace the button of the snap

switch, a grooved disk provided with a slot in which the winding key of the alarm clock is received, whereby the disk will be held for rotation with the said key when the alarm is struck, a cord secured to the disk in the 20 groove therein, a similar cord secured to the outer end of the arm, and a spring connecting the ends of the two cords.

In testimony whereof, we affix our signatures, in presence of two witnesses.

JAMES B. SMITH.
YANCY D. LOTT.
